WO WO 2010/132377 11/2010

Primary Examiner — Eric L Goodman

Assistant Examiner — Amy C Wierenga

(74) Attorney, Agent, or Firm — Remenick PLLC

CLAIM

The ornamental design for a wearable fluid-containing vest, as shown and described.

DESCRIPTION

FIG. 1 is a perspective view of a wearable fluid-containing vest showing my new design; and,

FIG. 2 is a top view thereof, the bottom view being identical. The evenly broken lines that appear throughout the figure set depict perforation lines in the wearable fluid-containing vest.
